BINDING MECHANISM.

1,188,392.

Specification of Letters Patent. Patented June 27, 1916.

Application filed December 30, 1912, Serial No. 739,281. Renewed January 7, 1916. Serial No. 70,890.

To all whom it may concern:

Be it known that we, BERT R. BENJAMIN and CLEMMA R. RANEY, citizens of the United States, residing at Oak Park and Chicago, respectively, in the county of Cook and State of Illinois, have invented certain new and useful Improvements in Binding Mechanisms, of which the following is a full, clear, and exact specification.

10 Our invention relates to binding mechanisms and especially to those adapted to use in connection with grain shockers and the like.

It has among its objects to guide and position in an improved manner the twine fed out from the binding needle of a binding mechanism.

15 A further object of our invention is to deflect the twine so fed out from a binding needle in such a manner that when adapted to use in connection with a shocking machine, the twine is withdrawn from the path of a shock discharged by the shock receptacle of the shocker and so positioned with 20 respect to that receptacle that when the first sheaf in the following shock is delivered thereto, it will carry the twine to the bottom of said receptacle in such manner that it will underlie the shock subsequently built 25 up therein.

30 A still further object of our invention is to draw off twine from the binding needle in such a manner that when used in connection with a shocker, the desired amount 35 of slack may be obtained and the twine may not be put under such tension as to interfere with the operation of the machine or be broken when it is carried down by the first sheaf in the next shock, or during the following binding operation.

35 We attain these objects by providing improved means coöoperating with the binding mechanism, which means automatically deflect the twine fed out from the binding 40 needle as it returns from each binding operation and draw off additional twine so that when used in connection with a shocker, the twine is held clear of a shock as the latter is discharged from the machine and 45 in a position to be engaged by the first sheaf of the next shock and carried down thereby into the shock receptacle, all in the desired manner and as hereinafter more fully set forth.

In the accompanying drawings we have, 55 for purposes of illustration, shown one embodiment which our invention may assume in practice.

Figure 1 is a rear elevation of a shocker equipped with our improvement; Fig. 2 is 60 a detail view of the twine guiding and positioning means.

65 In these drawings we have illustrated a shocker of the type wherein a pivoted sheaf-receiving cradle 1 normally reclines on a shocker frame 2; a binding needle 3 is automatically movable transversely across the sheaves in the cradle to coöperate with a knotter 4 to bind the sheaves into a shock, and a pivoted compressor arm 5 coöperates 70 with the binding needle 3 to compress the sheaves prior to the completion of the binding process.

75 In this construction the binding needle 3 and compressor arm 5 are pivoted on opposite sides of the cradle 1, and move alternately toward and away from each other in substantially parallel planes, being automatically operated from a suitable source of power 6 through a binder shaft 7 and a pivotally connected arm 8 and a cam 9, respectively. The cradle is likewise operated from the binder shaft 7 through suitable connections 10 adapted to tilt the same 80 about its pivot 11 to vertical or shock-discharging position. The twine normally stretches across the top of this cradle so that it may be carried to the bottom thereof by the first sheaf delivered from the sheaf delivering mechanism (not shown). If, however, the twine extends directly between the 85 end of the needle 3 and the knotter 4, it is found that in certain instances the tops of the sheaves carried in the cradle engage therewith as the cradle is swung about its 90 horizontal axis to discharge the shock, thereby interfering with the operation of the mechanism and occasionally breaking the twine. It is further found that an insufficient amount of slack is provided in the 95 twine so that in the next binding operation, or when the first sheaf in the next shock is delivered to the receptacle, the twine is apt to be under too great tension, with the result that it interferes with the efficient operation of the machine and is occasionally broken.

In our improvement we provide means

which protrude into the path of the twine fed out from the needle 3 as the latter is returned to its normal position, and engage the twine, carrying it upward and backward out of the path of the sheaves. Obviously, this means may assume various forms. In the construction shown the twine guiding means is in the form of an arm or projection 12 carried upon a bowed resilient strap 13 fixed at both ends to the needle side of the compressor arm 5 and extending longitudinally thereof. This arm or projection 12 is preferably fixed at both ends to the strap 13 at a point between the ends of the latter, and is itself so bent or bowed that its sides form the legs of an isosceles triangle, while its peak projects angularly and to one side of the strap, as shown in Fig. 1. In a preferred form the arm or projection 12 is also formed of a round rod in order to avoid any danger of cutting or raveling the twine and to permit ready passage of the latter over the guide. Obviously, however, the twine guiding means may be made integral with the compressor arm if desired.

The operation of the device is as follows: When the compressor arm 5 is thrown down to compressing position, the binding needle 3 is likewise lowered into its down or binding position, the parts assuming the position shown in full lines in Fig. 1. In this position the twine is clear of the guide 12. At the completion of the binding process the binding needle and compressor arm are automatically returned substantially simultaneously to the up or dotted line position shown in that figure. The twine guide 12 then moves upward with the compressor arm under the twine fed out from the needle and raises the same to the dotted line position shown, wherein it is held out of the path of the sheaves in the cradle 1 as the latter is swung about its pivot to shock discharging position. It is here to be noted that as the twine guide is thus swung upward it automatically draws off an additional amount of twine, and thus, at the same time, insures the requisite amount of slack for the next binding operation. It is further to be noted that the twine is thus also positioned transversely with respect to the cradle and above the latter so that it can be carried down to the bottom thereof by the first sheaf in the next shock, the twine being readily disengaged from the twine guide when pulled downward by that sheaf and ample slack being provided so that no interference with the operation of the mechanism may result. Obviously, when the parts are again brought into compressing and binding position, since the twine is thus automatically disengaged from the projection there is no interference with the binding process.

While we have herein described one embodiment of our invention for purposes of illustration, it is, of course, to be understood that the same may be modified without departing from the spirit of our invention.

What we claim, and desire to secure by Letters Patent, is:

1. In a binder, a movable binding needle, a knotter coöperating therewith, and means independent of said knotter for deflecting laterally the twine fed out from said needle after each binding operation.
2. In a shocking machine, a movable binding needle, a knotter coöperating therewith, and automatic means independent of said knotter for deflecting laterally the twine fed out from said needle after each binding operation.
3. In a shocking machine, a movable binding needle, a knotter coöperating therewith, and automatic means independent of said knotter relatively movable with respect to said needle for deflecting laterally the twine fed out therefrom after each binding operation.
4. In a shocking machine, a movable binding needle, a knotter coöperating therewith, and supplemental means independent of said knotter coöperating with said needle to draw off a predetermined amount of twine therefrom between said knotter and needle as the latter returns from each binding operation.
5. In a shocking machine, shock binding mechanism, shock discharging mechanism, and means coöperating with said binding mechanism for deflecting the twine for said binding mechanism out of the path of a shock discharged by said shock discharging mechanism.
6. In a shocking machine, shock binding mechanism, shock discharging mechanism, and means operable after each binding operation for deflecting the twine for said binding mechanism out of the path of a shock discharged by said shock discharging mechanism.
7. In a shocking machine, a movable binding needle, shock discharging mechanism, and automatic means operable substantially simultaneously with said binding needle for deflecting the twine fed out thereby from the path of a shock discharged by said shock discharging mechanism.
8. In a shocking machine, shock binding mechanism, pivoted shock discharging mechanism, and automatic means for withdrawing the twine for said binding mechanism out of the path of a shock discharged by said shock discharging mechanism as the latter is moved about its pivot.
9. In a shocking machine, a frame, a movable sheaf receiving member carried thereon, means for binding a shock therein, and automatic means coöperating with said binding

mechanism for deflecting the binding twine therefor out of the path of a shock carried by said member.

10. In a shocking machine, a frame, a movable sheaf receiving member carried thereon, means for binding a shock therein, and automatic means operable after each binding operation for pulling the binding twine out of the path of the top of a shock 5 carried by said member.

11. In a shocking machine, a movable binding needle, a movable compressor arm, means for operating said members in substantially parallel planes, and means carried by said compressor arm for deflecting the twine fed out from said binding needle after each binding operation.

12. In a shocking machine, a binding needle, a knotter coöperating therewith, a compressor arm, means for operating said mechanism, and means carried on said compressor arm for deflecting the twine fed out by said needle as the latter returns from each binding operation.

25. 13. In a shocking machine, a binding needle, a compressor arm, means for moving said members substantially simultaneously in opposite directions in parallel planes, and means carried by said compressor arm for 30 deflecting the twine fed out from said needle.

14. In a shocking machine, a movable binding needle, a compressor arm, means for operating said members substantially simultaneously, and means movable with said compressor arm for withdrawing a predetermined amount of twine from said needle after each binding operation.

15. In a shocking machine, a frame, a 40 sheaf receiving cradle pivoted thereon, a

binding needle movable transversely of said cradle, a knotter coöperating therewith, and means for elevating the twine fed out from said needle out of the path of a shock carried by said cradle prior to the movement 45 of the latter about its pivot.

16. In a shocking machine, a frame, a rearwardly tiltable cradle mounted thereon, a binding needle pivoted on said frame at one side of said cradle and movable transversely across the same, a knotter coöperating therewith, and means movable with said binding needle for automatically elevating the twine fed out therefrom after each binding operation out of the path of a shock carried by said cradle.

17. In a shocking machine, a frame, a binding needle pivoted at one side thereof and movable across the same, a knotter carried on the opposite side of said frame coöperating with said binding needle, a sheaf-receiving cradle pivoted to said frame and normally reclining thereon between the needle and said knotter, a compressor arm pivoted to said frame, means for moving 60 said needle and compressor arm substantially simultaneously in substantially opposite directions, means for tilting said cradle about its pivot, and means carried by said compressor arm for pulling the twine fed 65 out between said knotter and said needle out of the path of a shock carried by said cradle after each binding operation.

In testimony whereof we affix our signatures in the presence of two witnesses.

BERT R. BENJAMIN.
CLEMMA R. RANEY.
